UNITED STATES PATENT OFFICE.

LOUIS MESSEUR, OF NEW YORK, N. Y.

FASTENING FOR POCKET-BOOKS, &c.

SPECIFICATION forming part of Letters Patent No. 303,941, dated August 19, 1884.

Application filed January 19, 1884. (No model.)

To all whom it may concern:

Be it known that I, LOUIS MESSEUR, a citizen of the United States, residing at New York, in the county and State of New York, have 5 invented new and useful Improvements in Fastenings for Frames of Pocket-Books, Satchels, and other Similar Articles, of which the following is a specification.

This invention relates to a fastening for 10 frames of pocket-books, satchels, and other similar articles, which is composed of an arm secured to one jaw of the frame and bent so as to extend over the second jaw, a nose or projection formed on this bent arm, and a finger- 15 piece secured to the second jaw, so that when the two jaws are brought together said nose or projection engages with the second jaw and retains the frame in a closed position, and that by placing the thumb against the finger- 20 piece and the first finger against the nose or projection the frame can be readily and conveniently opened.

In the accompanying drawings, Figure 1 represents a front view of a frame provided 25 with my fastening when closed. Fig. 2 is a side view of the same. Fig. 3 is a plan or top view. Fig. 4 is a side view of the frame when it is open.

Similar letters indicate corresponding parts. 30 In the drawings, the letter A designates a frame for a pocket-book, satchel, or other similar article, said frame being composed of two jaws, a b, which are connected by pivots c, as usually practiced. On the jaw a is firmly 35 secured an arm, d, which is bent so as to extend over the jaw b, and on this arm is formed a nose or projection, e, in such a position that when the two jaws are moved toward each other the projection e engages with the jaw 40 b and retains the same in a closed position.

In the example shown in the drawings the projection e is made in the shape of a ball, and when the two jaws are closed up it springs over the rounded top edge of the jaw b, and I consider this shape the most practical which 45 can be selected; but it is obvious that the form of the projection may be changed without departing from the spirit of my invention. On the jaw b is firmly secured a finger-piece, f, so that by placing the thumb against the projection e and the first finger against the finger-piece f the frame can be conveniently opened. 50 In the example shown in the drawings this finger-piece consists of a ball fastened to the upper end of a stud, which rises from the top 55 of the jaw b; but it is obvious that the form of the finger-piece may be changed.

What I claim as my invention, and desire to secure by Letters Patent, is—

1. A fastening for the frames of pocket- 60 books, satchels, and other similar articles, said fastening being composed of an arm secured to one jaw of the frame and bent so as to extend over the second jaw, a nose or projection formed on this bent arm, and a finger-piece 65 secured to the second jaw, substantially in the manner shown and described.

2. The combination, with a bag-frame consisting of jaws a b, of an arm, d, bearing a ball or enlargement, e, upon its free end, and 70 attached to one of the jaws in a plane parallel with the top thereof, substantially as described.

In testimony whereof I have hereunto set my hand and seal in the presence of two subscr- 75 ing witnesses.

LOUIS MESSEUR. [L. S.]
